O'BRIEN KELLEY

GUARD FINGER

Filed Feb. 12, 1925

Fig. 2.

Fig. 3.

Inventor

O'Brien Kelley.

Larry & Lacey, Attorneys

UNITED STATES PATENT OFFICE.

O'BRIEN KELLEY, OF COOTES STORE, VIRGINIA.

GUARD FINGER.

Application filed February 12, 1925. Serial No. 8,796.

To all whom it may concern:

Be it known that I, O'BRIEN KELLEY, a citizen of the United States, residing at Cootes Store, in the county of Rockingham and State of Virginia, have invented certain new and useful Improvements in Guard Fingers; of which the following is a specification.

This invention relates to guard fingers for mowing apparatus and has for its object the provision of a supplemental finger arranged to alternate with the usual guard fingers whereby to prevent entanglement of weeds or stalks with the mowing knives and thereby avoid choking of the operation. The invention is illustrated in the accompanying drawing and will be hereinafter fully set forth.

In the drawing:

Figure 1 is a plan view of a guard finger having my invention embodied therein, the knives being omitted;

Fig. 2 is a side elevation of the same, and Fig. 3 is a section on the line 3-3 of Fig. 1.

Referring to the drawing, the reference numeral 1 indicates a guard finger of the usual formation having a rear extension 2 whereby it may be secured to the finger bar and having an intermediate transversely grooved portion 3 in which the cutter bar reciprocates in the usual manner, the intermediate portion being extended laterally on one side to define a wing 4 between the front transverse rib or lug 5 and the rear extension 2 and coterminous with the rib. Projecting forwardly from the wing 4 is a supplemental finger 6 which is narrow relative to the guard finger 1 and is located midway between two adjacent guard fingers. This supplemental finger which tapers upwardly in cross section, as shown in Figs. 1 and 3 has its front end tapered, as indicated at 7, and its upper surface 8 is disposed somewhat below the knife-supporting surface 9 of the guard finger while the under side of the supplemental finger is disposed above the bottom of the guard finger. It is to be noted that the front end of the supplemental finger is disposed at or slightly in advance of the vertical plane of the front terminal of the knife-supporting surface 9, and it is also to be noted that a recess or notch 10 is formed at the rear end of the finger 6 and the end of the lug 5 to receive the abutting end of the meeting lug 5 on an adjacent

guard finger, the auxiliary finger being thus disposed midway between two guard fingers. By having the finger tapered upwardly in cross section, inclined side faces are formed and reduce to a minimum the likelihood of stones becoming wedged between the fingers and knives.

By the use of my supplemental finger weeds, stalks and other matter which tend to accumulate upon the stationary knives and clog the operation of the cutter are turned aside so that the cutter will at all times operate smoothly and easily and without interruption. The supplemental finger is of such form and dimensions that it does not add materially to the weight of the cutter and it may be added to cutting apparatus now in use at slight expense. An auxiliary finger is disposed between each two guard fingers through the entire length of the cutter and they may be provided at each end of the cutter. By their use, stones which tend to lodge on the knives and break or chip them are turned aside so that breakage of knives is practically eliminated and the cost of repairs minimized. While I have shown the auxiliary finger as provided on one side of each guard finger, it will be understood that they may be provided at either side of the guard finger or at both sides of alternate guard fingers.

Having thus described the invention, I claim:

1. A guard for mowing knives comprising a rear finger bar engaging portion, a forward finger portion formed with a blade supporting surface, side arms extending transversely from the rear end portion of said finger portion, and a supplemental finger extending forwardly from the outer end of one of said side arms, said supplemental finger being unobstructed throughout its length and tapered upwardly in cross section and having its upper face spaced well below the plane of the blade supporting surface of said finger portion and its lower face above the plane of the lower face of said forward finger portion and extending substantially parallel to the upper face of the supplemental finger throughout the greater portion of its length and terminating in an upwardly curved forward end portion.

2. A guard for mowing knives comprising a rear finger bar engaging portion, a forward finger portion formed with a blade supporting surface, side arms extending

transversely from the rear end portion of said finger portion, and a supplemental finger extending forwardly from the outer end of one of said side arms, said supplemental finger being unobstructed throughout its length and having its upper face spaced well below the plane of the blade supporting surface of said finger portion and the rear end portion of the supplemental finger being formed in its outer side portion with a recess extending across the outer end of the last mentioned side arm and forming a seat having a bottom and forward end wall and adapted to receive the free end portion of the other side arm of a companion guard.

3. A guard for mowing knives including a forward finger portion having a blade supporting surface, a rear finger bar engaging portion and a transversely extending knife bar receiving seat between the finger portion and finger bar engaging portion, arms extending transversely from opposite sides of

the rear end portion of said finger and of a depth to dispose their lower edges below the plane of the blade supporting surface of 25 the finger, one arm being of a greater depth than the other and having its outer end recessed to form a seat to receive the end portion of the corresponding other arm of a companion guard, a web extending rearwardly from the thickened arm and joined to said finger bar engaging portion and forming a continuation of said knife bar seat, and an auxiliary finger extending forwardly from the outer end portion of the 30 thickened arm opposite said web with its upper face below the plane of the bottom of the plane of the blade supporting surface of 35 said finger and unobstructed throughout its 40 length.

In testimony whereof I affix my signature.

O'BRIEN KELLEY. [L.S.]
